Primary Examiner — Rhea Shields**CLAIM**

The ornamental design for a two-button toothbrush handle, as shown.

DESCRIPTION

FIG. 1 is a perspective view showing my design; FIG. 2 is a front elevational view thereof; FIG. 3 is a rear elevational view thereof; FIG. 4 is a right side elevational view thereof; FIG. 5 is a left side elevational view thereof; FIG. 6 is a top plan view thereof; and, FIG. 7 is a bottom plan view thereof.

In FIG. 7, the broken lines are for the purpose of illustrating portions of the two-button toothbrush handle which form no part of the claimed design.
